[57] CLAIM

The ornamental design for an aerodynamic side skirt for
a truck, as shown and described.

DESCRIPTION

FIG. 1 is a perspective view of an aerodynamic side
skirt for a truck showing my new design;

FIG. 2 is a perspective view of an aerodynamic side
skirt for a truck showing a second embodiment of my
new design;

FIG. 3 is an enlarged side elevation view of FIG. 2; and
FIG. 4 is an enlarged side elevation view of FIG. 1.

The broken line showing of a truck or portions of a
truck cab shown in all four views of the drawing is for
illustrative purposes only and forms no part of the
claimed design.
